[57] CLAIM

The ornamental design for a flip-top can opener, as shown and described.

DESCRIPTION

FIG. 1 is a top plan view of the flip-top can opener showing my new design;

FIG. 2 is a right side elevational view thereof, the opposite side being a mirror image;

FIG. 3 is a bottom plan view thereof;

FIG. 4 is a front elevational view thereof; and,

FIG. 5 is a rear elevational view thereof.

The broken lines shown in FIGS. 1-3 are for illustrative purposes only.
